BRUSHLESS SHAVING CREAM

Wolf Kritchovsky, Chicago, Ill., assignor to Rit Products Corporation, Chicago, Ill., a corporation of Delaware

No Drawing. Application September 26, 1936,
Serial No. 102,700

15 Claims. (Cl. 167—85)

My invention relates in general to shaving cream. It relates more in particular to the so-called "brushless" shaving cream of the type which does not depend for its action upon the lathering effect of soap.

Preparations employed for shaving have in general a two-fold object. They soften the hair as well as the skin on the face by emulsifying the natural oil present on the skin, and they also lubricate the skin so that the razor will pass over the same easily.

Ordinary shaving soaps are made empirically without any thought of these two functions, but it will be obvious that they must to some extent perform both functions in order to be usable. Those skilled in the art have found that the use of ordinary soaps is not satisfactory and accordingly attempts have been made in the past to produce a shaving cream which would perform both functions required in a more satisfactory manner. These creams are made usually from free fatty acid, usually stearic acid, and sufficient soap to emulsify the stearic acid in water. Some spermaceti wax or paraffin or other waxes or similar compounds have also been used to make the cream non-vanishing. A mixture of types of substances described emulsified with a relatively large amount of water (sometimes with some glycerin added) is well known. When spread on the face, they leave a substantial deposit of the emulsified stearic acid and waxes which act as a lubricant to prevent the razor from pulling or scratching.

In most of these preparations, a thorough washing of the face is first necessary to remove the natural oils. Otherwise the cream of itself would not soften the beard. As a general rule, these creams are fairly efficient but they are still subject to considerable improvement to remedy their outstanding defects. One difficulty is that in order to function satisfactorily as a lubricant they must have a relatively large amount of fats or waxes in relation to the soap present and this causes them to be too greasy, making it hard to remove them from the face and from the razor. When the amount of wax in proportion to the soap present is decreased so that they can readily be washed from the face or razor, these creams do not lubricate well. Moreover, they all leave something to be desired from the standpoint of softening the beard. Still another shortcoming is that the emulsions are not sufficiently stable and in cold weather they freeze and the emulsions break. Moreover, they cannot be employed satis-

factorily when the water employed on the face is cold.

The principal object of my invention is the provision of an improved shaving cream.

Another object is the provision of a shaving cream which obviates all of the difficulties hereinabove set out.

Another object is the provision of a shaving cream which will soften the beard even though the beard has been washed only slightly or not at all before the application of the cream.

Other objects and features of the invention will be apparent as the detailed description progresses.

I have found a class of chemical substances, which, as far as I know, has never been employed in brushless shaving creams heretofore, to be highly efficacious in brushless shaving creams, the major ingredients of which are fatty acid such as stearic acid and water and the entire product emulsified completely. The emulsion product so produced has very excellent properties in softening the beard to a much greater extent than the conventional brushless shaving creams heretofore employed. It has a great advantage in being readily washed from the razor, while the remainder left on the face after shaving is as readily removed from the face by washing. The product also can be made of such consistency that, while it may be freely washed from the razor, it will not possess the undesirable property of falling from the razor during shaving.

The class of compounds which I have found useful for improving brushless shaving creams are the aromatic sulphonic acids or the sulphonic acid salts wherein the sulphonic radical is attached directly to the aromatic nucleus. The aromatic nucleus may also contain other groups such as halogen groups and alkyl groups with one or more carbon atoms but there must be at least one sulphonic radical attached to the aromatic nucleus. More particularly, the compounds are sulphonated derivatives of benzene, toluol, polynuclear hydrocarbons of the aromatic or hydroaromatic series in which there may, if desired, be one or more aliphatic, aromatic-aliphatic, or hydro-aromatic radicals attached to the aromatic radical. In the case of the polynuclear derivatives, such as those of naphthalene, I have obtained particularly good results if the polynuclear derivatives contain alkyl, aralkyl or hydro-aromatic radicals containing three carbon atoms and upwards.

Among the compounds of this class which are effective for my purposes are benzene sulphonic

acid, sodium salt, toluene sulphonic acid, sodium salt, iso-propyl naphthalene sulphonic acid and its salts such as the sodium salt, alpha-naphthalene sodium sulphonate, beta-naphthalene sodium sulphonate, butyl naphthalene sulphonic acid and its salts, anthraquinone sulphonates, benzyl naphthalene sulphonic acid and its salts, sodium salt of tetra-hydro-naphthalene sulphonate, and sodium salt of naphthionic acid. Still other satisfactory compounds may be illustrated by the following structural formulae:

As described above, the sulphonic acid derivatives may also contain other substituents and these may be such groups as hydroxyl groups, amino groups, nitro groups, and halogen groups, and the side chain may also be attached to such substituents as, for example, in the case of the following compound:

It will be understood that the sulphonic acid derivatives may be employed in the form of their free acids or their salts, particularly the alkali metal salts such as sodium and potassium.

55 The creams consist for the most part of a fatty body like stearic acid or any other normally solid fatty acid like palmitic acid, or similar normally solid higher organic acids, with or without a solid fat like hydrogenated fats, lard, vegetable fat, mineral fat or paraffin or any other fat or wax such as carnauba, synthetic waxes and the like. The quantity of the fatty body may range from 5 to 30%, depending upon the hardness of the particular vehicle. A certain proportion of soap 60 may be used, ranging from 2 to 10%, or may be omitted. Caustic alkali, such as caustic potash, may be employed, in which case it reacts with the fatty acid or the like to form a soap. The quantity of the aromatic sulphonic acid compound as 65 defined, may range from about 0.1% to 5%. Perfumes and antiseptic agents may be used in a small percentage as required. The water content preferably ranges between 50 and 80%. The resulting product is a cream of whatever consistency 70 may be desired; a cream which is stable, 75

which, when put on the face, spreads until a very thin layer is obtained, which readily softens the beard, and which washes off very easily with water by dissolving or dispersing in the water solution; a cream which will not thin out on the face and fall off the razor during shaving.

For the better understanding of those skilled in the art, I give hereinbelow some representative examples of brushless shaving creams made in accordance with the present invention:

	Parts
(1) Stearic acid	100
Glycerin	5
Soap	13
Caustic potash	13
Phenol	0.6
Water	364
Sodium salt of tetralin	3
	10
(2) Stearic acid	100
Glycerin	5
Soap	13
Caustic potash	13
Phenol	0.6
Water	362
Sodium silicate	5
Alpha-naphthalene sodium sulphonate	5
	20
(3) Stearic acid	65
Coconut oil fatty acids	15
Petrolatum	15
Paraffin	10
Iso-propyl naphthalene sodium sulphonate	5
Water	327.5
Wilkinite	20
10% caustic soda	32.5
	30

In compounding the ingredients, the water is 40 heated and the soap, if used, and the caustic potash or caustic soda are dissolved therein. Then the stearic acid is melted and run into the water in a thin stream while agitating the water, and agitation is continued after all of the stearic acid has been run in until a heavy emulsion has 45 been formed. The aromatic sulphonic derivative is then added as a result of which the whole composition thins out until at the temperature at which the addition is made (60 degrees C. to 65 degrees C.) it may, in some cases, be almost as thin as water. The emulsion is then allowed to cool, continuing to stir it while cooling if necessary, until it reaches a temperature of about 40 degrees C. The perfume and antiseptic are 50 then added. The cream is then completed and while still at approximately 40 degrees C. is placed in containers such as collapsible tubes or jars. Upon standing for a time, the emulsion again thickens to form a fine, homogeneous, 55 easily spreadable cream.

It will be appreciated that the examples set forth above are to be construed in an illustrative manner and not by way of limitation. Formulae of varying composition may be employed together 65 with my improving agents, as will be readily understood by those skilled in the art. The invention is, therefore, not to be limited except as defined in the appended claims.

What I claim as new and desire to protect by 70 Letters Patent of the United States is:

1. A brushless shaving cream comprising a plastic emulsion of oleaginous and aqueous materials and containing a minor proportion of an aromatic sulphonate.

2. A brushless shaving cream comprising a plastic emulsion of oleaginous and aqueous materials and containing a minor proportion of a sulphonate of an aromatic polynuclear hydrocarbon.
- 5 3. A brushless shaving cream comprising a plastic emulsion of oleaginous and aqueous materials and containing a minor proportion of a sulphonate of an alkylated or aralkylated polynuclear hydrocarbon.
- 10 4. A brushless shaving cream comprising a plastic emulsion of oleaginous and aqueous materials and containing a minor proportion of an alkylated or aralkylated derivative of a naphthalene sulphonate.
- 15 5. A brushless shaving cream comprising a plastic emulsion of oleaginous and aqueous materials and containing a minor proportion of a salt of iso-propyl naphthalene sulphonate.
- 20 6. A brushless shaving cream comprising a plastic emulsion of oleaginous and aqueous materials and containing a minor proportion of a sulphonate acid salt of a substituted polynuclear aromatic hydrocarbon.
- 25 7. The product of claim 1 wherein the oleaginous material constitutes, at least in part, a normally solid higher fatty acid.
- 30 8. A brushless shaving cream comprising a plastic emulsion of oleaginous and aqueous materials and containing a minor proportion of an aromatic sulphonate, the oleaginous material comprising, at least in part, a normally solid higher fatty acid, and the aqueous materials constituting at least 50% of the weight of the entire cream.
- 35 9. A brushless shaving cream comprising a plastic emulsion of oleaginous and aqueous materials and containing a minor proportion of a sulphonate of an aromatic polynuclear hydrocarbon, the oleaginous material comprising, at least in part, a normally solid higher fatty acid, and the aqueous materials constituting at least 50% of the weight of the entire cream.
- 40 10. A brushless shaving cream comprising a plastic emulsion of oleaginous and aqueous materials and containing a minor proportion of a sulphonate of an alkylated or aralkylated polynuclear sulphonate, the oleaginous material comprising, at least in part, a normally solid higher fatty acid, and the aqueous materials
- 45 constituting at least 50% of the weight of the entire cream.
11. The product of claim 1 wherein the ingredients are present in substantially the following proportions:
Per cent	5
Oleaginous material	5 to 30
Aqueous material	50 to 80
Sulphonate	1/2 to 5
12. The product of claim 2 wherein the oleaginous material constitutes, at least in part, stearic acid, and wherein the ingredients are present in substantially the following proportions:
Per cent	10
Oleaginous material	5 to 30
Aqueous material	50 to 80
Sulphonate	1/2 to 5
13. The product of claim 3 wherein the oleaginous material constitutes, at least in part, a normally solid higher fatty acid, and wherein the ingredients are present in substantially the following proportions:
Per cent	15
Oleaginous material	5 to 30
Aqueous material	50 to 80
Sulphonate	1/2 to 5
14. The product of claim 3 including a soap, and wherein the oleaginous material constitutes, at least in part, stearic acid, and wherein the ingredients are present in substantially the following proportions:
Per cent	20
Oleaginous material	5 to 30
Aqueous material	50 to 80
Sulphonate	1/2 to 5
15. The product of claim 5 wherein the oleaginous material constitutes, at least in part, a normally solid higher fatty acid, and wherein the ingredients are present in substantially the following proportions:
Per cent	25
Oleaginous material	5 to 30
Aqueous material	50 to 80
Sulphonate	1/2 to 5
16. The product of claim 5 including a soap, and wherein the oleaginous material constitutes, at least in part, stearic acid, and wherein the ingredients are present in substantially the following proportions:
Per cent	30
Oleaginous material	5 to 30
Aqueous material	50 to 80
Sulphonate	1/2 to 5
17. The product of claim 5 wherein the oleaginous material constitutes, at least in part, a normally solid higher fatty acid, and wherein the ingredients are present in substantially the following proportions:
Per cent	35
Oleaginous material	5 to 30
Aqueous material	50 to 80
Sulphonate	1/2 to 5
Soap	2 to 10
18. The product of claim 5 wherein the oleaginous material constitutes, at least in part, a normally solid higher fatty acid, and wherein the ingredients are present in substantially the following proportions:
Per cent	40
Oleaginous material	5 to 30
Aqueous material	50 to 80
Salt of iso-propyl naphthalene sulphonate	1/2 to 5
acid chemical compound	2 to 10
